BALL TWIRLING COORDINATION TOY

Henry C. Henderson, 1754 E. Sycamore,
El Segundo, Calif.

Filed Sept. 10, 1962, Ser. No. 71,645

Term of patent 7 years

(Cl. D34—15)

FIG.1.

FIG.2.

FIG.3.

FIGURE 1 is a perspective view of a ball twirling coordination toy showing my new design;

FIGURE 2 is a front elevational view thereof, a rear view thereof having an identical outline but not including the circular openings or central handle; and,

FIGURE 3 is a bottom plan view thereof, the handle being shown broken away for convenience of illustration.

The essential features of my design reside in the full line disclosure on the drawing.

I claim:

The ornamental design for a ball twirling coordination toy, substantially as shown and described.
